SANDWICH MACHINES

Arthur J. Griner, Westfield, N. J., assignor to National Biscuit Company, New York, N. Y., a corporation of New Jersey

Application August 23, 1950, Serial No. 180,931

11 Claims. (Cl. 107—1)

This invention relates to sandwich machines, and particularly to a machine that receives base cakes, crackers, cookies or the like at one end, forms them into sandwiches with an interposed filler and delivers the completed sandwiches arranged in stacks or groups of a predetermined number at the other end, ready to be wrapped or otherwise enclosed to form packets or individual servings.

In recent years, the demand by the lunch counter and restaurant trade for small packets each containing an individual serving of cookie or cracker sandwiches has increased so rapidly that high speed machines are necessary for production adequate to meet the demand. The present invention makes this possible by producing stacks of sandwiches at a rate higher than has ever been attained before and at a reduced cost. The invention also produces a superior product, in that the sandwiches are more uniform, the top and bottom cakes are in better registry, loss due to breakage and imperfect sandwiches is reduced substantially to the vanishing point and fewer operators are required.

In a preferred embodiment of the invention, the top and bottom covers of the sandwiches, which are termed cakes or base cakes, are fed by belts in a number of continuous rows to two continuously rotating feed cylinders spaced apart in the line of travel of the cakes and between which is a filler cylinder. Each feed cylinder has as many circumferential rows of cake holders as there are rows of cakes fed to it. The first cylinder removes a cake from each row and deposits it on an endless belt running just below all three cylinders. This belt runs at the same speed as the peripheral speed of all the cylinders. As the cake deposited on the belt by the first feed cylinder passes beneath the filling cylinder, it receives a measured quantity of filler and then is carried by the belt under the second feed cylinder where the top or cover base cake is placed on it to complete the sandwich. The sandwiches are then carried on by the belt to its delivery end and there transferred to a collecting or grouping cylinder which is timed so that as soon as each holder receives a group of sandwiches sufficient to form a packet or serving, usually four or five, the group will be delivered to a flight chain to be carried on to a packaging machine. The entire operation of forming and grouping the sandwiches is performed automatically and manual operation is entirely eliminated.

The invention may be embodied in many forms of apparatus and in the accompanying drawings there is illustrated a preferred form thereof to which reference is made for a full disclosure.

Fig. 1 is a longitudinal sectional view of a complete machine, wherein the base cakes are supplied to the feed cylinders from continuously driven overhead belts;

Fig. 19 is a side elevation, partly broken away, of the pusher or paddle wheel for sliding groups of sandwiches from the inner to the outer flights;

Fig. 20 is a view taken substantially on line 20—20 of Fig. 19, looking in the direction of the arrows, the paddles being cut away in part so as to show their operation more clearly;

Fig. 21 is a section taken substantially on line 21—21 of Figs. 1, 19 and 20, looking in the direction of the arrows;

Figs. 22, 23, 24 and 25 are detail views of the holders or cups on the flight chains;

Fig. 26 is a rear view of the right-hand end of the machine shown in Figs. 1, 2 and 3 looking in the direction of the arrows 26—26 in Fig. 2, showing how the belts, flights, collecting cylinder and paddle wheel are driven in synchronism from the same shaft that drives the feed cylinders;

Figs. 27 and 28 are somewhat diagrammatic plan and side elevation views, respectively, illustrating how the two main flight chains deliver the groups of sandwiches to packet wrapping and sealing machines.

General description

Referring first to Fig. 1, base cakes 25, 26, which may be crackers, cookies, wafers or the like stacked on edge, are carried by belts 27, 28 in a continuous horizontal column to delivery chutes 29, 30, which turn the cakes so as to present them in vertical stacks to the respective feed cylinders 31, 32. Filling material 33, such as peanut butter, fondant, or other suitable substance, is supplied by a pipe 34 to a hopper 35 from which pockets of an intermediate filler cylinder 36 are filled.

All of the cylinders 31, 32 and 36 rotate counter-clockwise as shown in Fig. 1 and at the same speed. Beneath the cylinders is the top run of a conveyor 37, that consists of a number of endless belts, one pair for each circumferential row of cake feeding units in the cylinders, see Figs. 2, 8 and 10. The conveyor 37 is driven at the same speed as the peripheral speed of the cylinders 31, 32, 36 and in the same direction as their lower surfaces. The horizontal distance between the axes of the three cylinders 31, 36 and 32 is an exact multiple of the circumferential distance between the feeding units in the respective feed cylinders so that exact registry of the cakes on the conveyor 37 with the filling units will be obtained. The axes of the cylinders are adjustable to obtain and maintain this registry at all times.

The conveyor 37 receives the cake to form the bottom of the sandwich from the first feed cylinder 31 and carries it beneath the filler cylinder 36 where a measured quantity of filler is deposited thereon. The cake with the filler is then carried under the second feed cylinder 32 where the top cake is placed on the filler to complete the sandwich. The sandwich is then carried on by the conveyor to a collecting cylinder 38, into the grippers of which the sandwiches are stacked by stacker arms 39 in groups sufficient to form a packet for individual service, usually four or five. The collecting cylinder 38 has as many circular rows of grippers as there are rows of units in the cylinders 31, 32 and 36. There are four circumferential rows of grippers and the grippers of the outer and inner rows are arranged in staggered relation to deliver their groups of sandwiches to outer and inner flight chains 40, 41 respectively, Figs. 13 and 20. The outer grippers deliver their groups into alternate holders 42 of the chains 40 and the inner grippers deliver their groups to holders 43, Figs. 1 and 20, of the inner chains 41, the holders 43 being horizontally aligned with alternate holders 42. The groups received in the inner holders 43 are slid by paddles of a pusher 44 into the vacant alternate holders 42 of flight chains 40, Figs. 1, 19 and 20. The groups of sandwiches are then carried by the flight chains 40 to the packaging machines indicated diagrammatically in Figs. 27 and 28, where they are wrapped and sealed to form the usual individual servings that have become so popular for between-meals snacks and at lunch counters and restaurants. As shown in Figs. 22 to 25, each holder 42 is open on two sides and is secured to a plate 42a which is fastened to brackets 42b formed integral with certain links 42c of the chains 40. The holders 43 are made similarly, except that plates 43a, Figs. 20 and 21, are long enough to be connected to both chains 41.

The feed cylinders 31, 32, filling cylinder 36, conveyor 37, stacker arms 39, collecting cylinder 38, flight chains 40, 41 and pusher 44 are all synchronized and driven from a single motor 45, Figs. 1, 4 and 5. The motor 45 is swingably mounted on a frame 46 of the machine and through a belt 47 drives a main drive shaft 48, which in turn drives a worm wheel 49 keyed to a short shaft 50 having a gear 51 that meshes with a gear 52 keyed to the hollow shaft 53 of the second feed cylinder 32. The gear 52 meshes with an idler 54 that drives a gear 55 fixed to the hollow shaft 56 of the filling cylinder 36. Similarly, the gear 55 meshes with an idler 57 that drives a gear 58 keyed to a hollow shaft 59 of the first feed cylinder 31.

The main drive shaft 48 extends to the right in Figs. 1 and 2 and through a worm wheel 60 drives a shaft 61 on which pulleys 62 are keyed to drive the conveyor belts 37. The stacker arms 39 are fixed to a shaft 61 and lie between pulleys 62 so that they operate between each pair of the belts 37 to push the sandwiches into the grippers, Figs. 1, 2 and 13. The flight chains 40, 41, the gripper cylinder 38 and pusher 44 are driven by suitable gearing from the shaft 61, as shown in Fig. 26.

Feed cylinders

The feed cylinders 31, 32 are identical in construction and operation and are illustrated in Figs. 6, 7 and 8. Each cylinder is driven from the respective hollow shaft 53 or 59 to which it is fixed. Each cylinder has a number of longitudinal channels 64, circular in cross-section, that open through the periphery thereof and form bearings for cake holder bars 65 and permit them to have a limited oscillating movement. Each holder bar has a flat outer face to which an arcuate stripper plate 66 is secured in alignment with the cakes in each delivery chute, Fig. 2, so as to form a pusher for removing the bottom cake from the stack as the bar passes therebeneath. At one end, each holder bar has an arm 67 carrying a roller 68 that runs in the groove of a cam 69, Figs. 7 and 8, to cause the bar to oscillate within its bearing in the cylinder. Each holder bar has four transverse bores 70, each of which communicates with flared transverse bore 71 leading to a vacuum chamber 72 within the feed cylinder. The feed cylinder rotates on a fixed shaft 73 having a longitudinal bore 74 connected to a source of air pressure. The bore 74 communicates with lateral passages 75 in a valve member 76 keyed to shaft 73. The member 76 has valves 77, 78 that control communication of the bores 71 and passages 75 with the vacuum chamber and air pressure, respectively.

The bottom cake is withdrawn from the stack in the delivery chute 29 or 30 at the top of a feed cylinder and deposited on the conveyor 37 beneath the cylinder as best shown in Figs. 6 and 7. When a cake holder bar 65 reaches the top of the cylinder, communication with the vacuum chamber is cut off by the valve 77, and the stripper plate 66 has contacted the bottom cake. At this time the flattened face of the holder bar is horizontal or parallel with the cake. The roller 68 is riding in the cam groove 69 which is shaped so as to oscillate the holder bar about its own axis and keep its flat face horizontal, or substantially so, until the bottom cake is pushed forward free from the stack. At this time, the bore 71 moves past the valve 77 which opens communication with the vacuum chamber 72 and by suction through passage 70 holds the cake to the bar as it is carried out and down to the bottom of the cylinder.

As the bar holding the cake 25 approaches the conveyor 37, it is again moved by the cam 69 so that its face and the cake are parallel with the conveyor. The bore 71 then communicates with the passage 75 and a slight air pressure assures deposit of the cake on the belt. The second feed cylinder of course deposits its cake on the filling that has been placed on the first cake during its passage beneath the filling cylinder.

Filling cylinder

The construction and operation of the filling cylinder 36 are illustrated in Figs. 9 to 12. The filling cylinder has four circumferential rows of six pockets each corresponding to the number of cake holders in each feed cylinder. Each pocket 80 comprises an insert in the cylinder in which a piston 81 is slidable radially. The piston is urged inwardly by a spring 82 and at its inner end has a roller 83 that rides on a cam 84 secured to a fixed shaft 85 on which the cylinder rotates. The cam 84 has three operative sections 86, 87, 88, Fig. 9, each of which covers about one third of the periphery of the cam. When the roller 83 is riding on the section 86, the outer face of the piston 81 is flush with the face of the cylinder. This is from the time the filling has been deposited on the cake until the pocket enters the hopper. The section 87 is lower than the section 86 and is at the top of the cam, i. e., beneath the hopper. As the roller 83 rides off the section 86, the spring 82 forces it into contact with the section 87, thus withdrawing the piston so as to form a pocket in the outer face of the cylinder. The inward withdrawal of the piston causes the pocket 75 to fill with filler 33 from the hopper and the trailing side

89 of the hopper constricts the flow of the filler and tends to pack it into the pocket above the piston. At each side of the hopper there is an adjustable doctor blade 90, 91 that prevents leakage of the filler along the cylinder. Suitable packing may be provided at either side in addition to the blade but ordinarily the blade alone suffices.

When the pocket leaves the hopper upon continued rotation of the cylinder, it is filled flush with filler 33 in an amount to form the filling for the sandwich. When the pocket is clear of the cylinder, the roller 83 rides up on the section 88 of the cam, which pushes the end of the piston and the filler outward beyond the face of the cylinder. As the pocket rotates downward, Fig. 9, it registers with a base cake 25 that has been placed on the conveyor 37 by the first feed cylinder 31, and just beyond its lowest point the charge of filler 33 is scraped from the face of the piston by a cut-off wire 92, Fig. 11, and deposited on the cake. In order to prevent any tendency of the cake 25 to shift while the filler is being deposited, a vacuum chamber 93 is arranged below the conveyor 37 so as to exert its influence on the base cake as it is carried thereover.

The cut-off wire 92 is fixed at one end to an adjustable bracket 94 and passes across the ends of a series of fingers 95. Its opposite end is secured to an adjusting peg 96 by which it is kept taut. As best shown in Fig. 11, the cut-off wire 92 is slightly beyond the lowest point of the cylinder so that as the cut-off occurs the piston 81 has begun to rise on its return trip to the hopper. The wire 92 is adjustable with the bracket 94 and fingers 95 both fore and aft and up and down with respect to the point of cut-off. This assures that the charge of filling will be free of the piston and be deposited on the cake in exact registry. One of the many advantages arising from the invention is that the thickness, and hence the amount, of the filling deposited on each sandwich may be controlled without stopping the operation of the machine, so that a given quantity of sandwiches may be produced to meet any required weight standard. This feature of the invention is carried out by varying the working relationship of the cam 84 and the piston rollers 83 so that the cavity formed when the piston is retracted to receive filling from the hopper 35 is made shallower or deeper as required. This is accomplished by forming the surface portion 87 of the cam 84 so that it inclines slightly upwardly from the cam portion 86 toward the cam portion 88 and by making the cam 84 rotatably adjustable. To this latter end, the shaft 85 on which the cam 84 is mounted is equipped with a worm gear 79 (Fig. 2) arranged to mesh with a worm 79a connected to a control knob 80 for rotating the worm, and hence the cam, in either direction. With this arrangement, when the cam 84 is in the position shown in Fig. 9 the highest point on the portion 87 is effective to determine the radial position of the piston at the time it is carried past the doctor blade 91 and the minimum depth cavity is provided. Rotation of the cam 84 counterclockwise in Fig. 9 presents a continuously declining surface of the cam portion 87 at the effective position relative to the doctor blade 91, allowing the piston to be retracted radially and increase the depth of the filling cavity to the extent required up to the maximum of adjustment. Obviously, if the adjustment is set for a deep cavity and a shallower cavity is desired, the cam 84 is rotated in a clockwise direction to the required extent.

Collecting cylinder

Each conveyor 37 consists of two narrow belts spaced slightly apart and the cakes or sandwiches span the space as shown in Figs. 2, 8 and 10. The stacker arms 39 operate between the spaced belts at their delivery end, Fig. 13, and push the finished sandwiches from the conveyor on to the horizontal platform of a guard plate 100 and then into the open jaws of one of the grippers of the collecting cylinder 38. The collecting cylinder has four cir-

cular rows or sets of grippers which operate in pairs. The two outer sets deliver their stacks of sandwiches directly into alternate holders 42 of the outer flight chains 40 and the inner sets deliver their stacks into holders 43 of the inner flight chains 41, from which they are subsequently slid sidewise by paddles 102 of the pusher 44 into the empty alternate holders of the outer chains.

The grippers rotate with the collecting cylinder but each is mounted on a shaft 103 that has an oscillatory movement with respect to the cylinder so that the forward movement of each gripper may be accelerated as it approaches the receiving position at the guard plate 100 and be retarded while the sandwiches are being stacked between the jaws. In Figs. 13 and 15 only one outer set of grippers is shown, except that at A and B two grippers of an inner set are shown to illustrate their staggered position with respect to the outer row. All of the oscillating shafts 103 are shown but grippers are not shown on alternate ones except at A and B. The grippers of both outer rows are mounted on the same oscillating shaft 103 and those of both inner rows are mounted correspondingly on a single shaft, so that pairs of outer grippers operate simultaneously but in alternation with the inner rows.

A gripper is shown in detail in Figs. 16 to 18. A fixed jaw or receiving plate 104 is secured to a body portion 105 that is rigidly secured to one of the oscillating shafts 103. A clamping finger or movable jaw 106 is loose on the shaft 103 and is urged to closed position, Fig. 17, by a coil spring 107 surrounding the shaft 103 and taking its purchase against the body portion 105 in front of the shaft and against the rear end of the jaw 106 on the other side of the shaft. A rock shaft 108 extends lengthwise of the collecting cylinder and through the body 105 of each simultaneously operating pair of outer grippers. Similarly a like shaft extends through each pair of simultaneously operating inner grippers. The shaft 108 is free to oscillate in the gripper body and has a cam nose 109 fixed thereto and positioned between the jaws 104 and 106.

Upon oscillation of the shaft 108 in one direction, the cam 109 will raise the jaw 106 against the tension of the spring 107 to open the gripper, as in loading position, Fig. 16, and upon oscillation in the opposite direction will release the movable jaw so that it will be moved by the spring 107 to closed position as in Fig. 17.

Each gripper jaw actuating shaft 108 has an arm 110 carrying a roller 111 that rides on a cam 112 formed on a stationary head 113, Fig. 14, and as the cylinder rotates the shaft is operated by the cam to open the gripper at leading and unloading points. The cam 112 is secured to the head 113 by bolts 112a which permit angular adjustment of the cam as best shown in Fig. 13.

As already stated, the two outer grippers in each row are secured to the same oscillatable shaft 103, and similarly each pair of inner grippers is fixed on another oscillatable shaft 103. The shafts 103 are journaled in bearings 114a and 115a, Fig. 14, in flanges 114 and 115, respectively, of framework 116 of the collecting cylinder. Each shaft has an actuating arm 117 equipped with a roller 118. The arms 117 for the two sets of grippers are mounted on opposite ends of the respective shafts 103, those for actuating the outer grippers being at the right, Fig. 14, so that their rollers 118 run in the groove of a cam 119 in a fixed head plate 120. The rollers 118 on the arms 117 of the inner pairs of grippers run in a cam groove 121 of the head 113 at the opposite side of the cylinder.

The cam grooves 119 and 121 are shaped so that as a gripper approaches the loading position, Figs. 13 and 15, the shaft 103 will be oscillated by its appropriate cam to move the fixed jaw 104 downward or forward quickly into position to receive a sandwich from the guard plate 100 and recede slowly so that the fixed jaw moves forward slower than the rotation of the collecting cylinder as a whole during the time that the gripper is being filled. The guard plate 100 is curved downward to provide a

guard that keeps the sandwiches from falling out as the gripper descends during the loading operation. When a gripper has received a group of sandwiches, three operations are accomplished in rapid succession. The cam nose 109 of the gripper that has just been filled releases the movable jaw 106 which is closed by the spring 107 to grip the sandwiches. At the same time, or substantially so, the next following gripper is moved forward rapidly by its cam 121 or 119 to receiving position and the cam 112 operates to raise the cam nose 109 of the same gripper to open the movable jaw 106 so that the open gripper is in position to receive the next sandwich that is pushed forward by the stacker arms 39. This is clearly shown in Fig. 13, wherein the gripper marked F has just been filled and closed and the gripper E, with its movable jaw open, has just been advanced to loading position. The gripper A in an inner row is shown in the background between E and F.

When the filled gripper advances slightly beyond its position at F¹, the cam nose 109 will open the movable jaw 106 and the group of sandwiches will slide from the gripper into a holder 42 that will be directly beneath it at that time. It will be noted that the jaw 106 remains open except for that interval in the rotation of the cylinder when the group of sandwiches is transferred from loading to depositing positions.

The pusher

The rotating pusher 44 as shown in Figs. 19, 20 and 21, operates to slide the groups of sandwiches that are collected by the inner rows of grippers from the inner flight holders to the alternate holders in the outer flights. As previously stated, the outer rows of grippers deposit their groups of sandwiches in alternate holders 42 of the outer flight chains 40 and the inner grippers deposit their loads in the holders 43 of the inner flight chains 41. The holders 43 are juxtaposed with respect to the empty alternate holders 42 and thus are spaced apart twice the distance between holders 42, Fig. 20.

The pusher has eight pairs of paddles 102 pivotally mounted on opposite sides of a hub 125 that is fixed to a shaft 126. The pairs of paddles 102 are mounted to swing laterally in opposite directions. Each paddle is forked so that as it approaches its lowest position, it will straddle a group of sandwiches in a holder 43, Figs. 20, 21. Rollers 127, 128 carried by the paddles ride along opposite faces of a cam 129 supported by a bar 130 between the sets of paddles. As best shown in Fig. 20, the groups of sandwiches in the holders 43 of the inner flights travel in alignment with the empty alternate holders 42 of the outer flights. As they pass under the pusher, the two groups are embraced by opposite pushers and as the rollers 127, 128 strike rises 129a of the cam 129, the pushers are swung outward gradually sliding the groups of sandwiches into the empty holders 42 of the outer flights. The cam 129 has dwells 131, and while the rollers are riding thereon, the pushers 102, due to their rotation, are lifted clear from the groups of sandwiches that they have just transferred to the holders 42. Springs 132 connected to each pair of paddles return them to neutral or inactive position as the rollers 127, 128 ride down the declining portions 129b of cam 129.

Power drive

Fig. 26 shows how the conveyor belts 37, the flight chains 40 and 41, the collecting cylinder 38 and pusher 44 are all driven in unison with the feed and filler cylinders from the same source of power. The shaft 48 has a worm 135 that meshes with the worm wheel 60 keyed to the shaft 61 that drives the belts 37. A pinion 136 on the shaft 61 meshes with an idler 137 which drives a second idler 138 keyed to a short shaft 139 on which there is a pinion 140 driving a gear 141 keyed to a shaft 142 of the collecting cylinder 38. The gear 141 also drives an idler 143 that meshes with a gear 144 keyed to the

pusher shaft 126. The pusher has eight pairs of paddles and the collecting cylinder has twelve grippers in each set, hence the ratio of the gears 142 and 144 is 3:2 so that the paddles will synchronize with the grippers and holders. The gear 137 also drives a gear 146 fixed to a shaft 147 carrying sprockets that drive the four flight chains 40, 40, and 41, 41.

Since they function only to carry groups of sandwiches from the collecting cylinder 38 to the pusher 44, the inner flight chains 41 are relatively short, extending just beyond the pusher 44, Figs. 1 and 26, where they pass over sprockets 148a keyed to a shaft 148 mounted in the machine frame.

The outer flight chains 40 are much longer and each carries its groups of sandwiches to one of the packaging machines PM1 or PM2, that are indicated diagrammatically in Figs. 27, 28.

It is necessary that the packaging machines be driven at the proper speed to wrap and seal the groups of sandwiches that are brought to them by the flights 40. In order to synchronize the packaging machines with the sandwich machine, the main drive shaft 48 has a sprocket 149 keyed thereto, Fig. 26, which through a chain 150 drives a power take-off shaft 151 from which the packaging machines preferably are driven.

Referring to Fig. 5, the motor 45 is mounted on a platform 152 that is fixed to a shaft 153 mounted on the rear frame. The shaft 153 has an arm 154 at the upper end of which is a screw threaded nut 155 through which an adjusting rod 156 passes, the rod being operable by a hand wheel 157. A pulley 158 which drives the belt 47 and shaft 48 is an adjustable split V-pulley. When effective on its largest diameter to drive the belt 47, shown in full lines in Fig. 5, the shaft 48 and entire machine will be driven at maximum speed. When the hand wheel has been actuated to lower the platform 152 to dotted line position, the pulley 158 will drive from its smallest effective diameter and the machine will be operated at minimum speed. The drive can be adjusted to secure any speed desired between maximum and minimum.

Partial vacuum in the chambers 72 of the feed cylinders and pressure in the passages 74, Figs. 6 and 8, and suction in the chamber 93 under the filling cylinder, Figs. 10 and 11, may be attained by any suitable means. There is shown in Fig. 1, by way of example, a blower 159 driven by a motor 160 that may be connected to provide suction in chambers 72 and 93 and slight pressure in passages 74.

In order to time accurately the operation of the grippers, Figs. 14 and 15, the heads 113 and 120 having the cams 121, 119 are angularly adjustable about the axis of the shaft 142. Each head has a number of arcuate slots 161 through which pass bolts 162 that are screwed into spaced bars 163, which in turn are fixed to the frame of the machine. By means of the arcuate slots, the cams 119, 121 may be angularly adjusted to obtain accurate timing.

In Fig. 2, there is shown a gear 164 on the shaft 61 that may drive an oil pump for force feed lubrication of the machine.

As shown in Figs. 1, 6 and 7, the chutes 29 and 30 receive the cakes from the belts 27 and 28 and present them in vertical stacks to the feed cylinders 31 and 32, which remove the bottom cakes and deliver them to the conveyor 37 for formation of the sandwiches. The chutes 29, 30 are identical in construction and are best shown in Figs. 6 and 6A. Each chute has a rear plate 165, which extends laterally the full width of the belts 27 or 28 that carry the four stacks of cakes, and has spaced rods 166 forming an open front for each stack of cakes. The rods 166 are secured, as by welding, to bosses 167 on an adjusting bar 168, which is adjustably connected to a nut 169 fastened to each side of the rear plate 165 so that the distance between front rods 166 and rear

plate 165 may be adjusted to care for variations in the size of the cakes and their rate of feed by belts 27, 28. The bar 168 is longitudinally adjustable so that the stacks of cakes can be aligned accurately with the holder bars 65 and strippers 66 on the feed cylinders. Side plates 170 and 171, preferably secured to the bosses 167, provide lateral guides for the cakes. The front bars 166 preferably are made from round rods so as to present the smallest frictional surface to the descending column of cakes, and being spaced apart they provide access to the cakes should they become jammed in the chute, or to remove a broken one, or for any other purpose.

An adjustable gate 172, Figs. 6 and 6A, is provided to permit the stripper 66 to strip the bottom cake only from the stack. As shown, the gate 172 comprises a fixed shaft 173 mounted in a pair of stationary arms 174 arranged at opposite sides of the chutes 29 and 30. To the shaft 173 a pair of brackets 175 are adjustably secured by set screws 176, and the free ends of the brackets are connected by a stop bar 177 fastened thereto by studs 178. The bar 177 comprises a rigid member 179 and an inner resilient member 180, the latter being provided to be engaged by the leading edge of the next to the bottom cake and absorb the shock caused by friction between the bottom and the next to the bottom cake tending to carry the latter forward during the stripping operation. In order to adjust the gate 172 so that cakes of different given thicknesses may be used in the machine, it is necessary only to loosen the set screws 176, rock the brackets 175 to bring the bar 177 to the desired position, and then set up the screws 176 to hold the bar in that position.

The cakes 25, 26 are stacked on edge on the belts 27, 28 and as they leave the belts they fall along a curved path, due to their forward velocity and the force of gravity, into vertical stacks in the chutes 29, 30. The front guide rods 166 and rear plate 165 are curved to approximate as closely as possible the path of the cakes falling from the belts thereby reducing to a minimum the friction in the chutes and the probability of jamming of the cakes.

In the accompanying drawings and the foregoing description, a preferred embodiment only of the invention has been shown and described and obviously many variations and modifications may be made therein and in its mode of application which will still be comprised within its scope. It is to be understood, therefore, that the invention is not limited to any particular form or embodiment, except insofar as such limitations are expressly set forth in the appended claims.

Having thus described my invention, what I claim is:

1. In a sandwich machine, the combination of two cake feed cylinders spaced apart, a filling cylinder located between the feed cylinders, an endless conveyor having its upper run beneath said cylinders and extending therebeyond to a delivery point, means for driving all three cylinders continuously in the same direction at the same peripheral speed and the conveyor at the same speed as the surface speed of the cylinders and in the same direction as their bottom surfaces, means for supplying cakes to the feed cylinders and filler to the filling cylinder operated to receive a cake at the top thereof and carry it to the bottom and there deposit it on the conveyor, a pocket in the filling cylinder operated to receive a measured quantity of filler at the top thereof and carry it to the bottom and deposit it on the cake delivered from the first feed cylinder, a holder in the second feed cylinder operated to receive a cake at the top thereof and carry it to the bottom and there deposit it on the filler carried by the cake deposited from said first feed cylinder to form a sandwich, a rotating collecting cylinder adjacent the delivery end of the conveyor, grippers on the collecting cylinder adapted to be brought by rotation of the cylinder successively into position to receive sandwiches from the delivery end of the conveyor and when filed

move them away, means for opening the grippers as they come into receiving position, a stacker for pushing successive sandwiches from the conveyor into an open gripper to fill it with a group thereof, means for closing the gripper when filled, and means including a common driving connection for synchronizing the rotation of the collecting cylinder and opening and closing of the grippers with the deposit of cakes and filler on the conveyor by the feed and filling cylinders.

2. In a sandwich machine, the combination of two cake feed cylinders spaced apart, a filling cylinder located between the feed cylinders, an endless conveyor having its upper run beneath the cylinders and extending therebeyond to a delivery point, means for driving all three cylinders continuously in the same direction at the same peripheral speed and the conveyor at the same speed as the surface speed of the cylinders and in the same direction as their bottom surfaces, means for supplying cakes to the feed cylinders and filler to the filling cylinder at their top surfaces, a holder in the first feed cylinder operated to receive a cake at the top thereof and carry it to the bottom and there deposit it on the conveyor, a pocket in the filling cylinder operated to receive a measured quantity of filler at the top thereof and carry it to the bottom and deposit it on the cake delivered from the first feed cylinder, a holder in the second feed cylinder operated to receive a cake at the top thereof and carry it to the bottom and there deposit it on the filler carried by the cake deposited from said first feed cylinder to form a sandwich, a rotating collecting cylinder adjacent the delivery end of the conveyor, grippers on the collecting cylinder adapted to be brought by rotation of the cylinder successively into position to receive sandwiches from the delivery end of the conveyor and when filled move them away, means for opening the grippers as they come into receiving position, a stacker for pushing successive sandwiches from the conveyor into an open gripper to fill it with a group thereof, means for closing the gripper when filled, means including a common driving connection for synchronizing the rotation of the collecting cylinder and opening and closing of the grippers with the deposit of cakes and filler on the conveyor by the feed and filling cylinders, a flight chain running beneath said collecting cylinder, said chain having spaced holders that register with the successive grippers as they reach the bottom of the cylinder, each holder being adapted to receive a group of sandwiches from a gripper, and means for opening each gripper when it registers with a holder, whereby the groups will be deposited in the holders and carried from the machine.

3. In a sandwich machine, the combination of a pair of spaced-apart cake feed cylinders and an intermediate filling cylinder, an endless conveyor having the receiving end of its upper run beneath said cylinders and its delivery end extending therebeyond, said cylinders operating successively to deposit a cake on the conveyor, deposit filling on said cake, and deposit a second cake on said filling to form a sandwich, a flight chain equipped with holders having its upper run leading from a point adjacent the delivery end of the conveyor, a collecting cylinder arranged above the flight chain at the delivery end of the conveyor, said collecting cylinder being equipped with means for successively receiving a plurality of sandwiches and holding them in a stacked group, means for successively transferring sandwiches from the delivery end of the conveyor to said holding means on the collecting cylinder, means for effecting the transfer of the groups of sandwiches from said holding means to the holders on the flight chain, and means including a common driving connection for effecting the continuous synchronized operation of said conveyor, the feed and filling cylinders, the sandwich transfer means, the collecting cylinder and the flight chain.

4. In a sandwich machine, the combination of a pair of spaced-apart feed cylinders and an intermediate filling

cylinder, an endless conveyor having the receiving end of its upper run beneath said cylinders and its delivery end extending therebeyond, said cylinders operating successively to deposit a cake on the conveyor, deposit filling on said cake, and deposit a second cake on said filling to form a sandwich, a pair of flight chains equipped with holders having their upper runs leading from a point adjacent the delivery end of the conveyor, each chain having spaced-apart holders with those on one chain being adapted to register with alternate holders on the other chain, a collecting cylinder arranged above the flight chains at the delivery end of the conveyor, said collecting cylinder being equipped with two sets of means each operable for successively receiving a plurality of sandwiches and holding them in a stacked group, means for successively transferring sandwiches from the delivery end of the conveyor to said holding means on the collecting cylinder, means for effecting the transfer of the groups of sandwiches from one set of said holding means to the holders on said flight chain in register with alternate holders on the other flight chain and from the other set of holding means to the holders on said other flight chain between said alternate holders, means for sliding the groups of sandwiches from the holders of the one flight chain to the holders of said other flight chain in register therewith, and means including a common driving connection for effecting the continuous synchronized operation of said conveyor, the feed and filling cylinders, the flight chains, the collecting cylinder, the means for transferring sandwiches to the collecting cylinder, the means for transferring groups of sandwiches from the collecting cylinder to the holders on the flight chains, and the means for sliding groups of sandwiches from the one flight chain to the other.

5. In a sandwich machine, an endless conveyor having upper and lower runs comprising two parallel belts spaced apart, the upper run having receiving and delivery ends, means for driving the conveyor continuously, means for placing cakes in spaced-apart relation on the upper run at its receiving end and spanning the space between the belts, means for depositing a measured quantity of filling material on each cake while travelling with the conveyor, means for placing a top cake on each quantity of filling material to form a sandwich, said conveyor at its delivery end passing around a driving drum, a guard plate adjacent said drum adapted to receive sandwiches from said conveyor, a rotating stacker having radial arms operating between the belts of the conveyor to push the sandwiches from the belts to the guard plate, a collecting cylinder rotating on a horizontal axis adjacent said guard plate, a circular row of multiple sets of opposed grippers extending radially from the collecting cylinder adapted to be brought by rotation of the cylinder successively into position to receive sandwiches from the guard plate and when filled with a group of sandwiches to move them away, means for opening the grippers as they rotate into receiving position, means for closing the grippers when filled, and means for opening the grippers as they come to the bottom of the cylinder to discharge the groups of sandwiches.

6. In a sandwich machine, the combination of two cake feed cylinders spaced apart, a filling cylinder between the feed cylinders, an endless conveyor having its upper run beneath the cylinders, driving means for rotating all three cylinders continuously in the same direction at the same peripheral speed and for moving the conveyor at the same speed as the surface speed of the cylinders and in the same direction as their bottom surfaces, means for supplying cakes to the feed cylinders and filler to the filling cylinder at their top surfaces, a movable holder in the first feed cylinder formed with a flat cake supporting surface and operable to receive a cake at the top thereof and carry it to the bottom and there deposit it on the conveyor, a pocket in the filling cylinder operable to receive a measured quantity of filler at the top thereof and carry

it to the bottom and deposit it on the cake from the first feed cylinder, a movable holder in the second feed cylinder formed with a flat cake supporting surface and operable to receive a cake at the top thereof and carry it to the bottom and there deposit it on the filler on the first said cake to form a sandwich, and means associated with each feed cylinder for oscillating the cake holder of that cylinder, said means including a grooved plate cam stationarily mounted with respect to the feed cylinder, an arm on said cake holder carrying a roller arranged to ride in the groove of said cam, the cam being operable through said roller and arm as the cylinder turns to oscillate the holder and vary the angular position of said cake supporting surface relative to the surface of the cylinder during its transfer from the cake supply means to the conveyor, the groove being formed in the cam plate to oscillate the cake holder in timed relation to the rotation of the feed cylinder so as to present the cake supporting surface of the holder in a substantially horizontal position when receiving and depositing a cake.

7. In a sandwich machine according to claim 6, a filling cylinder rotatable on a horizontal axis, a hopper for filling material enclosing the top part of said cylinder, doctor blades sealing the space between the hopper and cylinder, a plurality of pockets equally spaced about the periphery of the cylinder, a radially slideable piston in each pocket, a spring urging each piston inward, a fixed cam within the cylinder, a roller on the inner end of each piston adapted to ride on said cam, said springs holding said rollers in contact with the cam during the complete rotation of the cylinder, the cam being shaped so as to permit each spring to withdraw its piston to form a cavity in the pocket while travelling within the hopper whereby the cavity is filled, the cam formed with a peripheral rise and dwell thereon to actuate the piston for extruding the filling and outer end of the piston beyond the periphery of the cylinder after it leaves the hopper and until it has passed its lowest point, and then permitting the spring to draw in the piston so that its outer face is flush with the cylinder until it again enters the hopper.

8. A sandwich machine according to claim 7, including means to vary the working relationship of said cam and roller to control the size of said cavity.

9. A sandwich machine according to claim 7, including means operable at will during the operation of the machine to vary the working relationship of said cam and roller to control the size of said cavity.

10. In a sandwich machine, an endless conveyor having upper and lower runs comprising two parallel belts spaced apart, the upper run having receiving and delivery ends, means for driving the conveyor continuously, a rotatable feed cylinder, means for rotating said cylinder, a plurality of cake holders mounted circumferentially in said feed cylinder, means to effect intermittent currents of suction and air pressure applicable through said cake holders in the placing of cakes in spaced relation on said conveyor upper run at its receiving end with the cakes spanning the space between the belts, a source of suction, a hollow suction chamber within said feed cylinder communicating with the source of suction, a source of air pressure, a fixed shaft for rotatably mounting said feed cylinder, said shaft having a longitudinal bore communicating with the source of air pressure, a plurality of transverse bores in said cake holders, and valve means for successively connecting the transverse bores with said suction chamber when the cakes are in transfer toward the conveyor belt and with the air pressure bore when the cakes are being discharged onto said conveyor belt, means for depositing a measured quantity of filling material on each cake while the latter is travelling with the conveyor, a second rotatable feed cylinder, means for rotating said second feed cylinder, a plurality of cake holders mounted circumferentially in said second feed cylinder, means to effect intermittent currents of suction and air pressure applicable through said cake holders in the placing of a top cake on each quantity of filling material to form

a sandwich, a hollow suction chamber within said second feed cylinder communicating with said source of suction, a fixed shaft for rotatably mounting said second feed cylinder, said shaft having a longitudinal bore communicating with said source of air pressure, a plurality of transverse bores in said cake holders, and valve means for connecting the transverse bores with said suction chamber when the cakes are in transfer toward the conveyor belt and with the air pressure bore when the cakes are being discharged onto said filler material.

11. In a sandwich machine, an endless conveyor having upper and lower runs comprising two parallel belts spaced apart, the upper run having receiving and delivery ends, means for driving the conveyor continuously, a pair of spaced apart rotatable feed cylinders arranged in line above the upper run of the conveyor, means intermediate the feed cylinders for depositing filling material onto a cake delivered to the conveyor from the first in line feed cylinder, means for rotating the feed cylinders, a plurality of cake holders mounted circumferentially in each of said feed cylinders, an air passage bored through each cake holder, a supply of cakes, a source of air suction, a source of air pressure, valve means associated with each feed cylinder operative by the rotation of the cylinder to control communication between the bores in said cake holders and the sources of suction and air pressure to effect intermittent currents of suction and air pressure through the bores in said cake holders, the suction being effective through the bores in the cake holders of the first in line feed cylinder when cakes are being delivered thereby from said supply toward the conveyor belt and the air
